NICOTINIC ACID ESTER OF CERTAIN HYDROXY-ALKYLENEIMINO-DIACETAMIDES

Joseph Seifter, Berwyn, and Roy S. Hanslick and Meier E. Freed, Philadelphia, Pa., assignors to American Home Products Corporation, New York, N.Y., a corporation of Delaware

No Drawing. Filed Aug. 7, 1958, Ser. No. 753,634

2 Claims. (Cl. 260—295.5)

This invention relates to chemical compounds of the amide type and, more particularly, to carbalkoxyamino-di-fatty acid amides, their salts, and methods for producing them. This application is a continuation-in-part of application Ser. No. 629,444, filed December 20, 1956, now abandoned, which, in turn, was a division of application Serial No. 495,038, filed March 17, 1955, now Patent No. 2,780,646.

The compounds of the invention, in the form of the free bases, may be represented by the formula:

wherein R₁ and R₃ are intended to stand for lower alkyl radicals while R₂ and R₄ stand for aralkyl radicals and R₅ representing selected acid ester-substituted lower alkyl radicals. The aralkyl radicals R₂ and R₄ may represent phenyl- or substituted phenyl-lower alkyl radicals wherein such substituents as lower alkyl, lower alkoxy, hydroxy, halogen, nitro, amino, mono- or di-lower alkylamino radicals may be on the ring. In the case of aralkyls of the β -phenylethyl type, hydroxy substituents on the β -carbon of the alkyl are also contemplated. With regard to R₅, the lower alkylene portion of the radical should have from 2 to 4 carbon atoms.

The present invention deals specifically with nicotinic and benzoic acid esters and the R₅ heterocyclic or aromatic ring may either be substituted or unsubstituted. If substituted, such substituents as lower alkyl, lower alkoxy, benzyl ether, hydroxy, halogen, nitro, amino, mono- or di-lower alkyl amino groups may be present to the extent of one to three substituents on the ring.

It has been discovered that compounds meeting the described qualifications, whether as the free base or the acid-addition salts, possess pharmacological activity and particularly surprisingly good local anesthetic action. The latter action has been noted when R₅ represents a hydroxy-lower alkyl or the above-mentioned esters of the hydroxy-lower alkyls. The replacement of the hydroxy group with an amino radical, for example, destroys the local anesthetic action as found in testing the compound

Additionally, where R₅ involves a straight-chain alkylene

2

group of more than 4 carbon atoms, no local anesthetic action could be found as discovered in testing

From the accumulated evidence, it therefore appears that 10 the local anesthetic action is selective for certain compounds and, further, that no prediction with regard to local anesthetic action is possible where R₅ represents other radicals.

Compounds falling within the scope of the formula as 15 given above may be used in the form of their acid-addition salts while still retaining their effectiveness for local anesthetic use. The salts provide great flexibility in therapeutic use since they may impart various degrees of water-solubility to an otherwise substantially insoluble base. 20 With regard to the acid-addition salts, either organic or inorganic acids may be used as long as they do not substantially increase the toxicity of the compound. Among the salts considered useful for the purposes indicated are the hydrochloride, sulfate, phosphate, hydrobromide, acetate, tartrate, propionate or succinate.

In preparing the di-fatty acid amides, where the amides are similar, the free bases are prepared by reacting a lower alkanolamine with an alpha-halo-fatty acid amide in a molar ratio of 1:2, but preferably the latter being present 30 in slight excess of this ratio. On the other hand, where the fatty acid amides are dissimilar, as, for example, where R₂ differs from R₄ or where R₁ differs from R₃, the bases are prepared by reacting an alkanolamino-fatty acid amide with a halo-fatty acid amide in a molar 35 ratio of about 1:1. The halogen atom may be either chlorine or bromine. The alkanolamino-fatty acid amide is prepared as taught by the general procedure outlined in the patents to Bruce et al. 2,568,142, dated September 18, 1951, or 2,654,754, dated October 6, 1953, suitably modified, of course, to provide the proper amine and halogenated reactants.

The reaction of the alkanolamine or alkanolamino-fatty acid amide and halo-fatty acid amide is carried out 45 substantially under the conditions as described in the above-mentioned patents. The reaction temperature is in the range of about 80° to about 200° C. but is preferably in the narrower range of about 100 to about 180° C. Alcohols of 3 to 7 carbon atoms, anisole, dioxane, hydrocarbon solvents, such as xylene, or, in fact, any inert 50 solvent boiling within the ranges indicated are suitable, the reaction taking place at the refluxing temperature of the solvent. Acid acceptors or mildly basic material are also provided for the reaction, these acceptors being, for example, pyridine, an alkali or alkaline earth metal oxide, 55 carbonate or bicarbonate or like substances.

The esters are easily formed from the alkanol compounds by known procedures. Typical methods involve reacting the alkanol di-fatty acid amide with an acid, acid anhydride, acid or acyl halide, with the anhydride and halide being preferred. The reaction is carried out 60 in a suitable inert solvent, such as hydrocarbon or chlorinated hydrocarbons, typical examples being benzene, toluene, chloroform and dichloromethane. An alkaline material may be provided as an acid acceptor for the reaction, if necessary, this being either alkaline metal hydroxide or carbonate or a tertiary amine. The temperature for esterification depends on the reactants and may range from about 0° to about 150° C.

The salts may be prepared in any manner known to 70 one skilled in the art. For acid-addition salts, one generally dissolves the free base in a suitable solvent and adds the selected acid thereto. The preparation of acid-

addition salts is well known and need not be described here.

The following examples illustrate the preparation of typical compounds falling within the scope of the invention.

EXAMPLE 1

Preparation of: N,N-di-(N-methyl-N-omega-phenyl-tert.-butylacetamido)-beta-aminoethyl nicotinate and salt thereof

Two grams (0.004 mole) N,N-di-(N-methyl-N-omega-phenyl-tert.butyl-acetamido)beta-hydroxyethylamine was dissolved in 50 cc. dry benzene. 0.9 gram (0.004 mole) nicotinic acid anhydride was added and the reaction refluxed 16 hours. The reaction mixture was cooled and nicotinic acid (M.P. 234-235° C.) was filtered off. The filtrate was concentrated under vacuum to syrup. This was taken up in acetone and refiltered. The filtrate was treated with dry hydrogen chloride. The precipitate was filtered, washed with acetone and dried. M.P.: 158-159° C.

ANALYSIS

	N	Cl
Fnd.....	8.74	11.33
Calc.....	8.93	11.35

EXAMPLE 2

Preparation of: N,N-di(methyl-N-[omega-phenyl-t-butyl]acetamido)aminoisopropyl nicotinate and salt thereof

N,N-di(N-methyl-N-[omega-phenyl-t-butyl]acetamido)amino-isopropanol (1.2 grams, 0.002 mole) and nicotinic acid anhydride (0.5 gram, 0.002 mole) in 50 cc. anhydrous benzene was refluxed 16 hours. After cooling the reaction mixture was washed twice with a saturated aqueous solution of sodium carbonate, then three times with water. The benzene layer was dried over magnesium sulfate and filtered; the filtrate was then concentrated to a syrup. The free base was dissolved in acetone-ether (1/1) and precipitated with dry hydrogen chloride as the hydrochloride salt. Recrystallization from acetone-methanol yielded the product as hydrochloride-dihydrate. M.pt.: 149-51°.

EXAMPLE 3

Preparation of: gamma-N,N-di(N-methyl-N-benzyl-acetamido)aminopropyl nicotinate and salt thereof

To a refluxing solution of 2.2 grams (0.01 mole) nicotinic acid anhydride in 100 cc. dry benzene was added 4 grams (0.01 mole) N,N-di-(N-methyl-N-benzyl-acetamido)aminopropanol. Refluxed 16 hours, cooled and removed nicotinic acid by filtration. The filtrate concentrated to a syrup. The base was redissolved in ether-acetone (1/1), and treated with a slight excess of dry hydrogen chloride. This oil, after decanting off solvent was dissolved in a small amount of water and obtained as a hydroscopic powder.

EXAMPLE 4

Preparation of: N,N-di(N-methyl-N-[phenyl]-isopropyl-acetamido)aminoethyl nicotinate and salt thereof

To 8.8 grams (0.02 mole) N,N-di-(N-methyl-N-[phenyl]-isopropyl acetamido) aminoethanol in 50 cc. dry toluene was added one drop 50% sodium dispersion and the reaction refluxed. Ethyl nicotinate, 3 grams (0.02 mole), was added and refluxing continued 3 hours. About 20 cc. toluene distilled off slowly under slight vacuum. After cooling the solution was washed with water, dried over magnesium sulfate. Toluene removed under vacuum. The oily residue was washed by trituration with hexane twice. A portion of the oil base in either was converted to a hydroscopic hydrochloride which was vacuum dried.

We claim:

1. A compound of the group consisting of di-fatty acid amides and the non-toxic acid-addition salts thereof, said amides having the general formula

wherein R₁ and R₃ represent lower alkyl radicals, R₂ and R₄ stand for phenyl-lower alkyl radicals and the term "alk" represents a divalent alkylene radical having from 2 to 4 carbon atoms.

2. The compound, N,N-di(N-methyl-N-omega-phenyl-tert.butyl-acetamido)-beta-aminoethyl nicotinate.
